BY Jobaboty ATTORNEY

United States Patent Office.

ISAAC KELLER, OF RANDOLPH, OHIO.

Letters Patent No. 79,476, dated June 30, 1868.

IMPROVEMENT IN HORSE-POWERS.

The Schedule referred to in these Letters Patent and making part of the same.

TO ALL WHOM IT MAY CONCERN:

Be it known that I, ISAAC KELLER, of Randolph, in the county of Portage, and State of Ohio, have invented new and useful Improvements in Horse-Powers; and I do hereby declare that the following is a full, clear, and exact description of my invention, reference being had to the accompanying drawings, forming a part of this specification, and to the letters of reference marked thereon, of which drawings—

Figure 1 is a plan of my improved horse-power.

Figure 2 is an elevation of the same.

Figure 3 is a section made by plane $x y$ in fig. 1.

The nature of my invention consists in the placing of all the multiplying-gear of a horse-power in a solid metallic box, whereby the gear is kept from the dirt when the power is sitting on the ground, and all the gear-wheels which move with considerable velocity are secured in a uniform position with respect to each other, thus insuring a uniform movement, and preventing any binding and undue friction and wear, as must be the case when the gear is hung in boxes on the separate pieces of the frame, and the frame is sprung or strained out of its exact original form by any outside action.

To enable others skilled in the art to make and use my invention, I will proceed to describe its construction and operation.

The main frame of my horse-power is composed of the sills C C, which are united by the cross-pieces D D, E E, as shown.

On the centre cross-piece D is placed the centre-plate T, on which turns the hub S of the master-wheel A B, which is secured in this position by the centre-bolt R, as shown in fig. 3.

The master-wheel is composed of the rim A, of cast metal; of the cross-section shown in fig. 3, and with gear on the lower face of it, and has the lips e e cast on the inner face, to which the arms B B, (which cross and are secured to the hub S,) are secured.

The holes a a are cast in the rim A, and levers are passed through them into the holes b b in the hub S, and the horses being attached to the ends of said lever, their power is communicated to the master-wheel.

The irons F F F, of the form shown, are arranged on the cross-pieces D D, and serve to secure a true rotation of the master-wheel, notwithstanding irregularities in the plane of application of the power.

The multiplying or speeding-gears P J K are hung on axles H I, the wheel P meshing into the gear on the lower face of the rim A of the master-wheel, and the wheels J and K meshing into each other.

A universal joint, L, is arranged on the end of the shaft I, to which the shaft M, (which transmits the power to the machine to be driven,) is attached.

The box G, which contains the gear P J K, is made in general form, as shown, and has at each side the lips d d, which support the box on the cross-pieces E E, and also serve for the lower part of the boxes for the journals of the shafts H and I; the upper part of these boxes being the covers e e, which are secured to the lips d d by bolts k k, which pass through the covers e e, the lips d d of the box G, and the cross-pieces E E, and also serve to secure the box G in its proper position on said cross-pieces.

The iron, N, is made, in general form, as shown, and is secured on the cover e by the bolts k k, and has a lip, n, which projects over the lower flange of the rim A of the master-wheel, and which prevents the master-wheel from rising up, so as to throw its teeth out of gear with the wheel P.

A small hole, g, is made in the lowest portion of the box G, which lets off any water which might accumulate in said box, and which would burst the box if allowed to remain and freeze.

It is readily seen that this arrangement keeps the gears P J K free from any dirt which they might scrape up were they not kept from the ground by the box G, and that they will not be made to bind by any rocking of the frame C D E, as they are all hung on the axles H and I, which run in boxes on the sides of the solid box G, which will not yield to any rocking of the frame, and also that the iron, N, with its lip n, insures the gearing of the master-wheel A and the first wheel B, as shown.

Having thus fully described my improved horse-power, I do not claim, as my invention, any part of the frame C C D D E E, nor the master-wheel A B B, nor the centre-plate T, centre-bolt R, the gear P J K, axles H and I, universal joint L, shaft M, or covers e e; but

What I do claim as my invention, and desire to secure by Letters Patent, is—

1. The solid metallic box G, with hole g therein, when used to contain the speeding-gear P J K of a horse-power, substantially in the manner and for the purpose set forth.
2. The iron, N, with lip n, when used in combination with the box G, with its gear P J K, and the master-wheel A B B, substantially as and for the purpose herein specified.
3. The peculiar arrangement and combination of the box G, axles H and I, with gear-wheels P, J, and K thereon, iron, N, with lip n, and master-wheel A B, the several parts being arranged in the manner and for the purpose herein specified.

As evidence that I claim the foregoing, I have hereunto set my hand in the presence of two witnesses, this 26th day of March, A. D. 1868.

ISAAC KELLER.
